UNITED STATES PATENT OFFICE.

STEPHEN A. AKINS, OF MERWIN, MISSOURI.

GAME APPARATUS.

SPECIFICATION forming part of Letters Patent No. 707,291, dated August 19, 1902.

Application filed December 13, 1900. Renewed July 7, 1902. Serial No. 114,641. (No model.)

To all whom it may concern:

Be it known that I, STEPHEN A. AKINS, a citizen of the United States, residing at Merwin, in the county of Bates and State of Missouri, have invented certain new and useful Improvements in Game Apparatus; and I do declare the following to be a full, clear, and exact description of the invention, such as will enable others skilled in the art to which it appertains to make and use the same.

This invention relates to game apparatus in general, and more particularly to that class wherein a ball is shot from a holder to traverse one of a number of paths to indicate different numbers which are counted on the total for the game, the object of the invention being to provide an apparatus with which an entertaining game may be played by both young and old.

20 A further object of the invention is to provide a novel and useful means for determining the score made at each shot of the ball, as also to provide an arrangement wherein the ball will have a positive operation each time it is shot.

In the drawings forming a portion of this specification, and in which like numerals of reference indicate similar parts in the several views, Figure 1 is a perspective view showing the complete apparatus. Fig. 2 is a section taken through one of the indicators and showing it in its dormant or normal position; the operative position of the indicator being indicated in dotted lines. Fig. 3 is a section taken 35 through the bell and its striker. Fig. 4 is an elevation showing the board and its stand, the board being in unfolded position ready for playing and adjusted to uncover the support for the lid of the box which the board 40 is in the form of. Fig. 5 is a view similar to Fig. 4 and showing the board in its closed or folded position. Fig. 6 is a longitudinal section taken vertically through one side of the apparatus, this view showing a board in 45 horizontal position instead of its normal slanting position.

Referring now to the drawings, the game apparatus comprises a stand which includes a center block 10, provided with supporting-legs 11, and pivotally mounted upon the up-

per end of which is a block 12, this block being provided with a cross-beam 13, fixed thereon, one half of the upper face of this cross-beam being horizontal, as shown at 14, while the face 15 of the other half of the beam is inclined from its outer end to the center of the beam, both ends of the inclined face portion of the beam being in a plane above the upper face of the opposite end of the beam. Extending laterally from the side 55 faces of the inclined end of the cross-beam are flanges 16, and these flanges are slidably engaged with the guide-slots 17 in the depending flanges 19 on the bottom of the section 20 of a case, this case including also a 60 section 21, the two sections being hinged together, so that the case may be opened and closed. The case may be slid to the outer end of the portion 13 of the cross-beam, and it may be then opened to lie with the section 65 21 upon the portion 14 of the cross-beam and resting directly upon a rubber or other yieldable stop 23. The section 21 of the case is of greater height than the section 20, so that the upper edges of the two sections when the 70 case is opened will lie in a common plane. The flanges with which the case is engaged are inclined, so that when the case is opened it will lie in an inclined plane, the game being played with the lower edge of the case next 75 to the player. The game apparatus specifically is disposed in the section 20 of the case, while the counter is located in the section 21.

The section 20 is in the form of an enclosure, as illustrated, and disposed transversely 80 thereof are a number of ribs 30, disposed parallel and diagonally of the member 20, and between these several ribs are alleys 31 of substantially equal dimensions. The ribs terminate at their left-hand ends—that is, at 85 their uppermost ends—spaced slightly from the inner or left-hand side of the member 20, which is the hinge side thereof, so that a runway 33 is formed, from which the alleys 31 branch, as shown, and in the operation of the 90 apparatus a ball is thrown or shot from the lower end of the runway toward the upper end thereof, so that it may in its return movement enter and pass through an alley, there being a return-passage 34 at the outer ends 95 100

of the ribs between them and the side of the casing. The ball is shot by means of a gun consisting of a block 35, which is secured at the lower end of the runway and through which is formed a cylindrical passage communicating with a perforation in the end of the casing. A plunger-head is disposed in the passage in the block, and the stem thereof is passed outwardly through the perforation in the casing, this outer end having an enlargement to limit its inward movement. An elastic band 37 is disposed transversely of this rear end of the stem of the plunger and has its ends attached to the end of the casing, so that when the plunger is drawn rearwardly and then released it will be moved violently forward and will discharge the ball which has been previously placed in the bore of the gun—i. e., the passage in the block. The path taken by the ball in its return movement determines the score of the shot, and to indicate the score without disclosing the numbers of the passages before the shot is made a series of tumblers are provided, one for each alley. The tumblers in question are shown at 38, and each consists of a metallic plate having ears 39 depending therefrom, and through the ears of all of the tumblers is passed a common pivot-rod 39', which is fixed upon the upper edges of the ribs 30, near the outer ends thereof, the ears at their lower portions lying between the ribs to prevent lateral displacement of the tumblers. On the under side of each tumbler is marked a number indicating the score of that alley, and depending from the inner end of the tumbler is a finger 40, which lies in and transversely of the alley and in the path of the movement of the ball through the alley, so that the ball may strike it and move the tumbler pivotally to reverse its position. A stop-bar 41 is disposed upon the ribs 30 in position to receive and support the tumblers in their reversed positions. The uppermost alley, lying between the uppermost rib and the end of the case, has no tumbler, so that the ball in passing therethrough will make no score, while the next alley, which is the most difficult to make the ball go through, is provided with a bell which is operated when the ball passes through the alley. The bell, which may be a common form of gong, as shown, is mounted upon a supporting-post, while the clapper 42 has its rod pivoted upon a rod 42' upon the ribs 30, between the bell and an arch 43, the ends of which latter are mounted upon the ribs 30 at opposite sides of the arch. The upper end or head of the clapper is in position to strike the gong when the clapper is swung pivotally, while the lower end of the clapper depends into the alley and in position to be struck and operated by the ball when passing through the alley. The numbers on the tumblers progress from "10" to "90," beginning with the lowermost tumbler, while the bell indicates "100," although it will of course be understood that the tumblers and

bell may be given any other numbers or otherwise marked, as desired.

In order that the scores made by the players may be recorded, a counter is provided and is placed in the section 21 of the case. This counter consists of a block 45, having a number of longitudinal series of holes, the face of the block being painted in stripes of different colors, each stripe including a single series of holes, and for these holes are provided a number of pairs of pins, the pins corresponding in number to the number of stripes. Each player has two pins of different colors, corresponding to the colors of two mutually adjacent stripes on the counter. The holes of one stripe count part way through the game, and the holes of the second stripe count the rest of the way through the game, and by using the pins they may be placed in the holes of the corresponding stripes to indicate the score.

It will of course be understood that in practice various modifications of the structure shown may be made and that any suitable materials and proportions may be used for the various parts without departing from the spirit of the invention. Furthermore, the apparatus may be used for scoring in different ways and may be used for different specific games, the pivotal mounting of the structure upon the stand permitting the players to remain in their chairs while the apparatus is swung from one to another of them.

What is claimed is—

1. A game apparatus comprising a runway, a gun at one end of the runway, a plurality of alleys leading laterally from the runway, and a reversible tumbler pivoted above each alley and having a portion depending into the alley for engagement by a body passing through the alley to reverse the tumbler and a common support disposed to receive the tumblers in their reversed positions.

2. A game apparatus comprising a runway, a plurality of alleys leading laterally from the runway, a gun at one end of the runway and adapted to discharge a ball along the runway, the outermost alley being unobstructed, a bell, a striker for the bell pivotally mounted with one end in an alley for engagement by a body discharged from the gun and passing through the alley to operate the striker, and a reversible tumbler for each of the remaining alleys, each of said tumblers having a depending portion lying normally in its respective alley for engagement by a body discharged from the gun, to operate the tumbler.

3. A game apparatus comprising a runway, a plurality of alleys leading laterally from the runway, a gun at one end of the runway to discharge a body through the runway, a bell mounted above a runway, a pivoted clapper or striker having a portion depending into an alley for operation by a body passing through the alley, a pivot-rod disposed transversely of the alleys, a reversible tumbler for

each of the remaining alleys mounted upon the pivot-rod and adapted for reversal, a depending portion on each tumbler lying normally in its respective alley for engagement by a body passing through the alley to operate it, and a common rest-bar disposed to receive the tumblers in their reversed positions.

In testimony whereof I hereunto sign my name, in the presence of two subscribing witnesses, on the 30th day of October, 1900.

STEPHEN A. AKINS.
